C STEPHANO.
RECEPTACLE.
APPLICATION FILED MAY 8, 1917.

1,262,992.

Patented Apr. 16, 1918.

Inventor:
Constantine Stephano
by his attorney Charles G. Hensley,

UNITED STATES PATENT OFFICE.

CONSTANTINE STEPHANO, OF ELKINS PARK, PENNSYLVANIA.

RECEPTACLE.

1,262,992.

Specification of Letters Patent. Patented Apr. 16, 1918.

Application filed May 8, 1917. Serial No. 167,187.

To all whom it may concern:

Be it known that I, CONSTANTINE STEPHANO, a citizen of the United States, and a resident of Elkins Park, in the county 5 of Montgomery and State of Pennsylvania, have invented certain new and useful Improvements in Receptacles, of which the following is a specification.

My invention relates to receptacles in 10 which merchandise may be sold. The receptacles are especially useful as containers of cigarettes in lots of one hundred or any other quantity, where it is desired to have a container of more substantial material 15 than the small cigarette packets.

The principal object of my invention is to provide a receptacle composed of sliding or telescoping parts having a label, revenue stamp or other paper device pasted on the 20 several parts of the receptacle whereby the paper must be torn or cut to open the receptacle, together with means, such as a cord, for tearing the paper on a line which will render the parts of the receptacle 25 slideable one on the other. In attaching revenue stamps to cigarette containers it is required that they be so attached that the stamp must be broken when the container is opened and it is often unhandy to break or cut the 30 stamp to open the container unless a knife or other instrument is used. With the present device there is a member in the nature of a cord lying under the stamp, which goes out with each receptacle; and by pulling on 35 this cord the stamp may be broken on a line which will unseal the receptacle.

I am aware that it has heretofore been proposed to employ a cord under the seal or wrapper of a package to facilitate opening 40 it but my object herein is to so dispose the cord in relation to the receptacle that it will not bulge and cause the stamp or seal to be worn through where the receptacles are packed together and where the cord would 45 otherwise tend to wear through the stamp or seal. The cord is so disposed, furthermore, that it will not be displaced during handling of the receptacle.

Another object of my invention is to provide a simple arrangement for preventing side play or wobbling between the telescoping parts of the receptacle.

In the drawing forming part of this application,

55 Figure 1 is a perspective view of the receptacle, closed and sealed,

Fig. 2 is a similar view, showing the back of the receptacle,

Fig. 3 is a perspective view of the receptacle opened and showing how the inner 60 flap may be turned back when a cigarette is to be taken out,

Fig. 4 is a perspective view of one of the telescoping parts of the receptacle separated from the other, and showing the stamp 65 severed along the edge,

Fig. 5 is a sectional view, taken on the line 5—5 of Fig. 1, and

Fig. 6 is a sectional view taken on the line 6—6 of Fig. 4. 70

The receptacle is preferably made to exclude air whereby it will serve as a humidor. In the drawing the receptacle 1 comprises the telescoping inner and outer members 2 and 3. The member 2 consists of a bottom, 75 side walls 5, and the end wall 6. The end of the member 2 opposite the end wall 6 is preferably left open to receive the cardboard lining. The member 2 also has a short top section 7 partially closing the top of this 80 member.

The member 3 consists of a top wall 8, bottom wall 9, side walls 10 and 11 and an end wall. Both members 2 and 3 may be made of one or more sheets of tin bent to the 85 desired shape and seamed along the meeting edges.

The member 3 is preferably turned over at its edge 12 around the sides and top to increase the thickness of the edge and to 90 make it smooth. The member 2 has a shoulder 13 formed across the top 7 and both sides 5 corresponding with the shape of the edge 14 of the member 3; that is, if the edge 14 of the member 3 is straight around the top 95 and sides then the shoulder 13 on member 2 is preferably straight also. The shoulder at 15 on the bottom of the member 2 is in line with the shoulder 13 of the sides 5, but it extends forwardly at 16 forming a projection beyond the general line of the shoulder 15. The member 3 has its edge on the bottom recessed at 17 to correspond with and receive the projecting portion 16 of the shoulder of the member 2. When the member 3 is placed over the member 2 as in closing the receptacle, and then moved until the projecting portion 16 of the shoulder rests against the recessed portion 17 of the edge of the member 3 the receptacle will then be 100 closed as far as it is intended to be. The projection 16 of the shoulder beyond the

105

110 projection 16 of the shoulder beyond the

straight parts 13, 15 is so proportioned that when the receptacle is completely closed the projection 16 will hold the members sufficiently apart to provide a slight space 18 5 between the edge 14 of the member 3 (around the two sides and top) and the shoulder 13. This space or recess is intended to receive a cord or similar member 19 therein so that the cord will not project or bulge above the 10 surface of the receptacle. When the paper 20, which may be the internal revenue stamp, label, or whatever is used to seal the receptacle, is pasted over the members 2 and 3 at the top and sides and across the space 15 or gap 18 it will lie flat just as if the cord were not present, so that there can be no objection to the use of the cord in this manner. As the cord does not project above the top 20 surface of the receptacle the paper will not be worn through by the cord as would be the case if the cord caused the paper to bulge and therefore rub against receptacles stacked 25 against it. To open or unseal the receptacle it is only necessary to grasp one of the free ends of the cord 19 and pull outwardly from the box and this will tear the paper along the edge 14 whereupon the members 3 can be moved along the member 2.

In making metal telescoping receptacles, 30 it is not practicable to have them fit very tightly one over the other and therefore there is a tendency for one part to move sideways in relation to the other. In the present device this is avoided. The projecting portion 35 16 of the shoulder can be accurately stamped, and likewise the recess 17 in the edge of the member 3 may be accurately stamped to agree with the projection 16. When these parts are brought together there 40 will be no lateral play between the members 2 and 3 because of the closeness of these parts, even if the walls of the member 3 do not fit snugly to the walls of the member 2.

There is preferably provided a cardboard lining 21 fitting around the interior of the receptacle and it has a short flap 22 slightly longer than the short top portion 7 of the member 2. There is another flap, 23, having its edge overlying the edge of the flap 22 and it is adapted to be turned up from the scored line 24. The fingers may be passed into the cut outs 25 to raise the flap 23 when it is desired to take a cigarette.

Having described my invention, what I 55 claim is:

1. An article of the class described comprising relatively sliding members adapted to telescope one over the other and together forming a receptacle, one of said members 60 having a shoulder formed thereon, and means for limiting the closing position of said members whereby the end of the outer receptacle member will be spaced from said

shoulder to provide a recess, a cord lying in said recess and a strip or stamp secured to 65 the receptacle members across said recess and adapted to be severed by said cord to release said members.

2. An article of the class described comprising inner and outer relatively sliding 70 members adapted to telescope one over the other and together forming a receptacle, said inner member having a shoulder formed thereon, said shoulder having a forwardly extending portion adapted to form an abutment for the open end of said outer member whereby when said members are closed the remaining portion of said shoulder will be spaced from the edge of said outer member to form a recess, a cord lying in said recess 80 and a strip or stamp secured to the receptacle members across said recess and adapted to be severed by said cord to release said members.

3. An article of the class described comprising inner and outer relatively sliding members adapted to telescope one over the other and together forming a receptacle, said outer member having a substantially straight edge around three of its sides at the open 90 end of said member and having its edge on the fourth side recessed across the major portion of said side, said inner member having a shoulder extending substantially straight, around three sides thereof, said shoulder having a forwardly projecting portion on the fourth side thereof corresponding with the recessed edge portion of said outer member, said projecting portion of said shoulder being adapted to limit the closing position of 95 said receptacle members whereby the said shoulder around three sides of the receptacle will be spaced from the end of said outer member to form a recess, a cord lying in said latter recess and a strip or stamp secured to 100 said receptacle members across said latter recess and adapted to be severed by said cord.

4. An article of the class described comprising inner and outer relatively sliding members adapted to telescope one over the other and together forming a receptacle, said inner member having a shoulder formed thereon, said shoulder having a forwardly extending portion adapted to form an abutment for the open end of said outer member 11 whereby when said members are closed the remaining portion of said shoulder will be spaced from the edge of said outer member to form a recess, and a strip or stamp secured to the receptacle members across said 12 recess and adapted to be severed to release said members.

Signed at the city of Philadelphia, county of Philadelphia and State of Pennsylvania, this 28th day of April, 1917.

CONSTANTINE STEPHANO.
